MULTIPLE FASTENER

Aulis E. Taskila, Negaunee, Mich.

Application September 10, 1936, Serial No. 100,180

1 Claim. (Cl. 24—205)

This invention appertains to new and useful improvements in multiple fasteners, and more particularly to a novel connector or slider element therefor.

5 The principal object of the invention is to provide a multiple fastener slider which can be taken apart to permit assembly on the fastener conveniently and quickly, which is at present a very marked difficulty when the slider runs off of the 10 teeth.

Other important objects and advantages of the invention will become apparent to the reader of the following specification.

In the drawing:

15 Figure 1 represents a fragmentary front elevational view of the improved fastener.

Figure 2 is an inside elevational view of one section of the fastener.

20 Figure 3 is an inside elevational view of the complementary section of the fastener.

Figure 4 is an end elevational view of the fastener.

25 Figure 5 is a section substantially on line 5—5 of Figure 4.

Referring to the drawing, wherein like numerals designate like parts, it can be seen that numeral 5 in Figure 1 represents a piece of fabric having a slit therein to the opposite longitudinal edge portions of which are secured the multiple 30 fastener side strips 6 which are connected or disconnected by the slider 7.

This slider is of novel construction and consists of the sections 8—9. The section 9 represents the top of the slider, while the section 8 represents 35 the bottom body of the section, the top body 9 consisting of the plate 10 having the converging arcuate-shaped side walls 11—11 and at its wide end provided with an upstanding body 12 which tapers inwardly and which is provided with a 40 longitudinally extending slot 13 for receiving the longitudinally extending rib 14 on the inwardly

tapering body 15 of the section 8, which body 15 is also located within the wide portion of the section 8. The sections interlock by the rib 14 engaging into the slot 13, and threaded openings 16—17 are provided in the bodies 12—15 to accommodate the screw 18 which is provided with a head 19 adapted to engage the cap section 9 from which extends the finger grip 20.

As is shown in Figure 2, the plate 21 of the section 8 is provided with converging side walls 22—22 and these side walls 11—11 and 22—22 in complement with the abutting bodies 12—15 define passageways 23—23 (see Figure 4) through which the teeth 6 are guided.

In the event the slider runs off of the teeth, the 15 cap section 9 can be removed by removing the screw 18 and the section 8 can be properly set on the teeth and the cap again applied without any difficulty.

20 While the foregoing specification sets forth the invention in specific terms, it is to be understood that numerous changes in the shape, size, and materials may be resorted to without departing from the spirit and scope of the invention as claimed hereinafter.

25 Having described the invention, what is claimed as new is:

A slider for multiple fasteners comprising a pair of plate sections each provided with a pair of converging side walls, each of said sections being provided with a body portion at its wide end, interlocking means between the said sections, said interlocking means consisting in the provision of a longitudinally extending slot in one of the bodies and a rib on the other body for engagement into the slot, said body portions having a transverse screw threaded bore therein, and a removable screw in said bore for securing said bodies together.
